UNITED STATES PATENT OFFICE.

WILHELM HÜBNER, OF BERLIN, GERMANY, ASSIGNOR OF ONE-HALF TO
BERNHARD KRÜGER, OF SAME PLACE.

SPITTOON.

SPECIFICATION forming part of Letters Patent No. 537,115, dated April 9, 1895.

Application filed August 15, 1894. Serial No. 520,414. (No model.)

To all whom it may concern:

Be it known that I, WILHELM HÜBNER, engineer, a subject of the Emperor of Austria-Hungary, residing at Berlin, Prussia, Empire 5 of Germany, have invented certain new and useful Improvements in Spittoon-Holders; and I do hereby declare the following to be a full, clear, and exact description of the invention, such as will enable others skilled in the 10 art to which it appertains to make and use the same.

This invention relates to a frame for spittoons and its object is to provide the same with mechanical self-acting covers in such manner as to keep them closed and satisfy all hygienic and æsthetic requirements.

In the drawings, Figure 1 is a side view of the spittoon holder showing the lid partially raised. Fig. 2 is a plan view of the spittoon 15 holder.

The frame consists of a wire ring *a* upon which the spittoon is suspended by its upper rim, and which is carried on four feet *c*, *c'*, *c''*, *c'''*. Two of these latter *c', c''* are provided with eyelets *d* in which the cover-frame *b* is fixed by means of bent wire arms or hooks *g*. One of these arms is provided in a suitable manner with a long oval eyelet or slot *h* also made of wire and projecting backward, in 20 which the free end of a wire tread-lever *f* is adapted to engage. This tread-lever, which is formed out of the prolongation of the foot *c'''* and hangs thereon by a short arm *e*, resting upon the floor with a loop *f'*, possesses on account of this mode of construction, a spring 25 action so that the end *f''* is made to exert an upward pressure whereby the cover is automatically closed.

When the cover is to be opened all that is 30 required is to put one's foot on the tread-lever *f* and press it downward as it is shown in Fig.

2 by dotted lines, so that the free end *f''* of the tread-lever *f* acting on the oval loop or eye *h* raises the cover frame in the direction of the arrow.

45

The frames *a* and *b* can be covered in any ornamental manner by any suitable material, according to fancy, for which ladies' work is especially suited; but they may also be covered with sheet-metal, papier maché, pasteboard, &c., with or without ornamentation, varnish, paint, &c.

Having now particularly described and ascertained the nature of my said invention and in what manner the same is to be performed, 55 I declare that what I claim is—

1. In a spittoon holder, the combination, with a ring *a* provided with feet and adapted to support a removable spittoon, of a lid for the spittoon hinged to the rear feet of the 60 frame and provided with the rearwardly projecting eyelet *h*, and a spring tread lever connected to one of the front feet and having its rear end sliding in the said eyelet, substantially as set forth.

65

2. In a spittoon holder, the combination, with a ring *a* provided with feet and adapted to support a removable spittoon, of a lid for the spittoon hinged to the rear feet of the frame and provided with the eyelet *h* of 70 twisted wire, and a spring tread lever formed of a prolongation of one of the front feet and provided with a loop *f'* bearing on the ground and an end sliding in the said eyelet, substantially as set forth.

75

In testimony whereof I have affixed my signature in presence of two witnesses.

WILHELM HÜBNER.
